UNITED STATES PATENT OFFICE.

ARTHUR A. BLUE, OF SEWICKLEY, PENNSYLVANIA.

AUTOMOBILE STORAGE CONSTRUCTION.

Application filed July 6, 1923. Serial No. 649,842.

To all whom it may concern:

Be it known that I, ARTHUR A. BLUE, a citizen of the United States, residing at Sewickley, in the county of Allegheny and State of Pennsylvania, have invented certain new and useful Improvements in Automobile Storage Constructions, of which the following is a specification.

My invention relates to automobile storage and has in view to provide means for loading, storing and removing a large number of machines, with a minimum space per machine and without loss of time or interference.

Generally stated, the invention provides one or a series of continuously connected and supported platforms in the manner of endless chain units, each platform providing for the housing of one or more machines. Each platform is supported at proper intervals for clearance across between opposite very strong substantial sprocket or other type of chains, carried, driven and controlled for purposes of elevation and stoppage at any predetermined level for each platform.

The invention also has in view to provide a system of such units, of any desired or practicable height, within a building having lateral entrance and exit, on a ground level, together with various other incidental features of construction and operation as shall be more fully hereinafter described.

Referring to the drawings, showing certain preferred embodiments of the invention,

Fig. 1 is a general plan view, showing a series of elevating storage units within a building;

Fig. 2 is a sectional end elevation of one of such units, partly broken away;

Fig. 3 is a view in elevation at right angles to Fig. 2, showing the driving gearing, motor, etc., for operating one of the head sprocket shafts;

Fig. 4 is an enlarged detail view of one end of the platform supporting hangers;

Fig. 5 is a view in elevation showing one of the supporting units, partly in section;

Fig. 6 is a similar view showing a modified construction;

Fig. 7 is a detail view showing the controlling lock for the suspended turntable of Fig. 6;

Fig. 8 is a detail sectional view showing the guide for the chain impelled supporting members; and

Fig. 9 is a detail view of a lock for the carrying chain.

In carrying out the invention, I provide one or a series of units A, B, C, D, etc., arranged side by side within a building E having entrance and exit door openings e in alignment with a driveway or alley f. The driveway is preferably of just sufficient width to allow clearance for a single car 65 and a limited degree of turning on to or off from one of the supporting platforms.

Said platforms 2 are of any suitable construction for strength and rigidity, preferably rectangular in form, supported at 70 each end by hangers 3, 3, from a cross rod or bar 4. The outer terminals of bar 4 extend through and form the connecting pin of sprocket links 5 of chains 6, 6, at each side, which in turn pass over and are supported and driven by head sprocket wheels 7, 7, and pass around similar bottom or tail sprocket wheels 8, 8, as in Fig. 2. Wheels 7, 7 and 8, 8 are spaced apart, as shown, for sufficient clearance and lateral separation 75 of the several platforms 2, with their loads in passing over from one to the other of either pair of sprocket wheels 7, 7, or 8, 8, as will be readily understood.

In this manner, each unit comprises two 85 vertically arranged tiers of platforms, continuously connected and supported by their chains, and movable up and down in opposite directions by means of the actuating mechanism provided.

The sprocket wheels are carried on the inner ends of stud shafts 9 carried in suitable bearings 10, avoiding the use of continuous cross shafts for the upper sprocket wheels, so as to leave intervening clearance 95 for the passage of the platform hangers at the top and of the platforms themselves at the bottom. One pair of the head sprocket wheels 7 is positively driven by a suitably controlled motor 11 through shaft 12 and 100 gearing 13, 14, 15, 16, for each opposite sprocket 7, whereby they and the chains 6, 6, are actuated together, and stopped and started at the proper time.

Each platform 2 is supported by the hangers 3, 3, at each opposite end from the pair of chains 6, and is preferably provided with a centrally arranged turntable 17. The turntable is mounted for easy turning on the platform by means of a central pivoting bolt 18 and an annular row of ball or roller bearings 19. The turntable is adapted to be

locked against accidental movement by means of a latch 20 engaging one of a series of peripheral notches 21, said latch forming a portion of a manipulating lever 22 at one side of the platform. The hangers 3, of any suitable construction are preferably mounted on the end portions of the cross bar 4 in such a manner as to provide for a limited range of vertical movement thereon, 10 as in loading and unloading.

For such purpose, the upper portion of the hangers are vertically slotted as at 23, and a strong stiff spiral spring 24 is interposed between the upper end of the slot and the bar, adapted to support the weight of the platform and its contents with a limited degree of resiliency. The purpose of such cushioning is to avoid sudden jarring or strains on the platform and the supporting 15 chains, especially in loading. As a further compensating and reinforcing precaution, I provide for a temporary local support of each platform by means of a plunger 25 having a supporting head 26 adapted to be raised by admission of fluid pressure to cylinder 27 through a valve controlled pressure supply pipe 28.

Such supporting mechanism is located below the receiving and delivering position 30 of each platform when at the floor level of alley way *f*, as clearly shown in Fig. 2. When the platform and its turntable are in receiving or delivering position and at the same level with the floor, as shown, the 35 plunger is raised below the platform, lifting it slightly or providing a solid bearing, during which time a car may be run on or off. Thereafter, the plunger is lowered out of the way, the elevating mechanism is started, the platform is raised or lowered one space, bringing the next empty platform into position, as in charging. When it is desired to unload any particular car, it is brought back to the floor level and 40 stopped, and the car is run off, such operation being repeated as frequently as it is necessary to either load or unload. As will be obvious, either an empty platform or a loaded one may be brought to the floor level 45 through the shortest travel by operating the motor forwardly or backwardly.

In Fig. 6, I show a modified construction of support in which the platform 2^a is rigidly carried by the hangers 3^a from the upper cross bar or frame 29. Said frame in turn 50 is pivotally connected by a central bolt 18^a and any suitable turntable support, as a depending disk 30, having roller bearings 31 upon which a co-acting supporting plate 32 of upper frame 29 rests. By such means, the platform 2^a may be rotated to any desired degree.

A locking latch 20^a is pivotally mounted on frame 29, as at 32^a, and connected by cables 33 to an operating lever 34, by which

the latch 20^a may be thrust upwardly into locking engagement with bar 4^a for holding the platform against rotation, or released for rotation, as desired.

While ordinarily the sprocket gearing will 70 securely hold the chains against accidental movement, due to overbalance at one side or for any other reason, I may provide an independent lock, such as is shown in Fig. 9. In such case, a dog or dogs 37 of lever 75 38 may be thrown temporarily between the links 5 of chains 6, so as to positively hold the chains against movement, until released.

When one unit as thus constructed, or a series of such units, is located as in Fig. 80 1 within a building, individual cars may be run along the alleyway *f* at either side, and on to any particular platform of either unit. Depending upon the height of the structure, the capacity of each unit may 85 vary within wide limits, and thereby provide for the storage of a large number of cars within a comparatively limited space as to area. The height of each platform as to its head clearance may be kept at a minimum so as to utilize the vertical space to the best advantage, and provide for the maximum capacity of cars within any given height. The platforms 2 may be properly numbered so as to be utilized in connection 90 with any suitable checking system, rendering it easy to very quickly bring to the loading or unloading floor level the particular platform desired.

For the purpose of guiding the platforms and maintaining them in vertical alinement at all times, and avoiding any swaying tendency, vertical guides, as channels 39, are 100 preferably located beyond the chains at each side and each cross bar 4 extends inwardly between the flanges of such channel, preferably with a roller 35, as in Fig. 8. If desired, two such rollers may be utilized, one on the bar and a lower one on the hanger as in Fig. 5, so as to more securely maintain the vertical aligning travel of the platforms at all times. The inner flange of such channel is cut out as at 36, for lateral clearance of such rollers or guiding abutments at suitable locations, providing for 105 lateral movement of the chain 6 at the top and bottom.

The advantages of the invention will be 110 readily understood and appreciated by all those familiar with the problem of automobile storage. The facility in handling a large number of cars within a minimum space and without confusion and obstruction, is a feature of especial advantage and economy.

It will be understood that the apparatus 115 may be variously changed or modified in different details of construction, size, adaptability to varying weights and designs of 120 cars or trucks, to suit local conditions or 125

demands of existing traffic, but all such changes are to be considered as within the scope of the following claims.

What I claim is:

- 5 1. In a storage system for motor vehicles, the combination with an enclosing building, of a series of continuously connected movable platforms comprising two main vertically arranged oppositely traveling 70 tiers spaced apart for clearance at top and bottom and with clearance space between them and the building walls for vehicle movement, and means for continuously supporting and moving all of the platforms 10 together, and means for independently supporting individual platforms at the floor level.
2. In a storage system for motor vehicles, the combination with an enclosing building, of a series of continuously connected 20 movable platforms comprising two main vertically arranged oppositely traveling tiers spaced apart for clearance at top and bottom and with clearance space between them and the building walls providing 25 alleyways for vehicle movement, chains continuously supporting and pivotally connecting the several platforms in serial spaced relationship, spaced apart pairs of 30 gears at top and bottom for supporting and actuating the chains and their supported platforms, and means for driving and controlling the gearing.
3. In a storage system for motor vehicles, the combination with an enclosing building, of a plurality of adjacent carrying and storage units each comprising a series of continuously connected movable platforms 35 consisting of two main vertically arranged oppositely traveling tiers spaced inwardly at the bottom from the building walls providing alleyways for vehicle movement, and means for continuously supporting and moving the platforms of each unit together, 40 and means between each unit and said supporting means providing for independent relative movement of individual units.
4. The combination with an enclosing building having a floor and a sub-recess 50 therein, and clearance space between the building walls and said recess at each side thereof, of a series of continuously connected movable platforms comprising two main vertically arranged oppositely traveling 55 tiers spaced apart for clearance space between adjacent platforms for a vehicle, means for continuously and flexibly supporting the platforms, and means for actuating the supporting means adapted to 60 bring the several platforms into registering relation with the floor.
5. In elevating and storing mechanism, the combination with a floor and a clearance pit, of a series of carrying platforms 65 and supporting and actuating chains there- for adapted to move the several platforms individually into registering alinement with the floor, and vertically movable means for temporarily supporting a platform at the floor level independent of its 70 chains.
6. The combination with supporting chains and means for actuating them, of a series of platforms having supporting hangers pivotally connected with the chains 75 and vertically movable means for temporarily supporting an individual platform independent of the chains.
7. The combination with supporting chains and means for actuating them, of a 80 platform having supporting hangers at each end pivotally connected with the chains, and cushioning mechanism providing for limited independent vertical movement of the hangers and platform. 85
8. The combination with supporting chains and means for actuating them, of a platform having supporting hangers at each end pivotally connected with the chains, cushioning mechanism providing 90 for limited independent vertical movement of the hangers and platform, and a vertically adjustable supporting abutment for the platform adapted to support it temporarily and relieve the tension on the chains. 95
9. The combination with two supporting chains, of a platform pivotally connected therewith at opposite sides and provided with a turn-table, and independent elevating mechanism adapted to relieve the chains 100 and temporarily support the platform and its load during rotation of the turntable.
10. The combination with two supporting chains, of a platform pivotally connected therewith at opposite sides and provided 105 with a turn-table, and means for locking the turn-table against rotation, and independent elevating mechanism adapted to relieve the chains and temporarily support the platform and its load during rotation 110 of the turntable.
11. In combination, a vertically arranged framework provided with pairs of oppositely located vertically disposed guiding channels having lateral clearance openings, continuous supporting chains arranged in conformity with said channels, laterally spaced pairs of chain wheels therefor at top and bottom, means for actuating said wheels, and series of platforms pivotally connected 115 with the chains and having guiding abutments beyond such pivotal connection engaging the channels, and supplemental guiding abutments on the platforms below and in vertical alinement with said abutments also engaging the channels. 120
12. In combination, a vertically arranged framework provided with pairs of oppositely located vertically disposed guiding channels having lateral clearance openings, 125

continuous supporting chains arranged in conformity with said channels, laterally spaced pairs of chain wheels therefor at top and bottom, means for actuating said wheels, and series of platforms pivotally connected with the chains and having cushioning mechanism providing for limited independent vertical movement of the platforms.

10 13. The combination with two supporting chains, of a supporting cross bar pivotally connected therewith at opposite sides and having a middle depending turntable supporting disk, and a platform having an upper cross member and disk rotatably

15 mounted on said disk with intervening rolling bearings.

14. The combination with two supporting chains, of a supporting cross bar pivotally connected therewith at opposite sides and 20 having a middle depending turntable supporting disk, a platform having an upper cross member and disk rotatably mounted on said disk, and locking mechanism on the cross member of the platform provided 25 with an operating lever and adapted to engage the supporting cross bar.

In testimony whereof I hereunto affix my signature.

ARTHUR A. BLUE.
